CLAIM

The ornamental design for a yoga wheel, as shown and described.

DESCRIPTION

FIG. 1 is a front, left and top perspective view of a yoga wheel showing my design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is an enlarged view of detail 8 in FIG. 1.

The broken lines in the drawing depict portions of the yoga wheel that form no part of the claimed design. The broken lines in FIG. 1 and FIG. 8 are used for the purpose of depicting the bounds of the enlarged figure and form not part of the claimed design.
